UNITED STATES PATENT OFFICE.

JAMES MCKINLAY, OF BROOKLYN, ASSIGNOR TO THE RICHARDSON & BOYNTON COMPANY, OF NEW YORK, N. Y.

STEAM OR HOT-WATER BOILER.

SPECIFICATION forming part of Letters Patent No. 374,615, dated December 13, 1887.

Application filed July 16, 1887. Serial No. 244,523. (No model.)

To all whom it may concern:

Be it known that I, JAMES MCKINLAY, a subject of the Queen of Great Britain, residing at Brooklyn, in the county of Kings and 5 State of New York, have invented new and useful Improvements in Steam or Hot-Water Boilers, of which the following is a correct description.

The invention has relation to the class of 10 hot-water heaters which are placed in a ground-story, basement, or cellar of a structure, and which are designed to warm upper apartments of such structure by means of a system of pipes which are warmed by the circulation 15 through them of a body of water which has been previously heated in the water chamber or chambers of the heater.

The object of the invention is to provide at 20 small cost a hot-water heater for domestic use, which shall be easily portable and through which water shall, through the operation of natural laws, pass rapidly upward in a thin volume or stream, with which the products of 25 combustion are, in effect, in continuous contact, so that the heat thereof is thoroughly utilized.

The invention consists in certain novel parts and in certain novel combinations of parts in a hot-water heater for domestic use, whereby 30 cold water as it is introduced at the lowest extremity of the water-containing portion of the heater is first permitted to pass into an annular uncorrugated receptacle, and is then passed upward along a corrugated portion of 35 the water-passage, in a contracted or spread-out volume, to a point in a plane with the top of the fuel and combustion chamber, where it is permitted to expand, and whence it is directed in a continuously-ascending stream to 40 a reservoir or expansion-chamber at the top of the heater, as will first be described with particularity, and then distinctly indicated in the claims.

In the drawings, Figure 1 represents the 45 furnace, in part in front elevation and in part in transverse vertical section, on the line *u u* of Fig. 2. Fig. 2 represents a vertical section from front to rear, as on the central line, *v*, in Fig. 1. Fig. 3 is a horizontal section in 50 the line at *w w* in Fig. 1. Fig. 4 is a horizontal section in the line at *x x* in Fig. 1. Fig. 5

is a top plan view of the lower water-chamber detached, and showing, also, the grate-bars at the lower extremity of the fuel-chamber, the inner wall of the annular water-chamber and 55 the wall of the fuel-chamber being identical. Fig. 6 is a transverse vertical section on the line *y y* of Fig. 3. Fig. 7 is a transverse vertical section on the line *z z* of Fig. 4. Fig. 8 is a horizontal section on the line at *tt* of Figs. 60 1 and 2. Fig. 9 represents a modified form of the water-tubes.

The heater is composed, essentially, of an ash-pit section, A, a water-chamber section, B, which embraces, also, the fuel-chamber, and 65 a combustion-chamber section, B², which embraces the water-chambers C, D, C', D', C², and E, placed one upon another in the order indicated, each resting in a suitable seat and all firmly secured together by bolts and nuts, (not shown,) 70 the joints being, by preference, packed with asbestos, although, if desired, the sections may be tapped and joined by means of pipe-nipples.

The base or ash-pit section A, preferably 75 having doors *a* and *a'* and hanger *a*³ for the support of the outer end of the actuating grate-bar *a*², is provided with inwardly-projecting annular flange *a*⁴, to receive the corresponding inturned flange *b*² of the uncorrugated exterior 80 shell, *b*, of the water-chamber B, such exterior shell having any desired number of openings, having threaded collars *b*³ near the base of the shell for attachment of water-supply pipes *p*. Near its upper extremity the shell *b* assumes 85 an approximately rectangular form, corners *b*⁴ being projected outwardly, as seen in Figs. 1, 2, and 5, to form an expansion-chamber, *b*¹³, and to produce correspondence in area and configuration with the superposed sections of 90 the heater, and the extreme upper portion of the shell having an outwardly-extending horizontal flange, *b*⁵, to receive the outer portion of a broad covering-flange, *b*⁶, which projects outwardly from a point near the top of the 95 inner shell, *b*', which from a point near the bottom thereof and in a plane with the top of the supply-pipe collars *b*³ is provided with vertical corrugations *b*⁷, which terminate upwardly at the top of the shell. The lower portion of this interior shell, *b*', on a level with the water-inlets is made plain, thus providing an 100

annular water-chamber, b^9 , which extends around the section, and which terminates downwardly at a point opposite the inturned annular flange b^8 , which is received upon the 5 corresponding flange b^2 of the exterior shell, which, it may here be remarked, is provided with a front fuel-supply opening and a corresponding door, B'.

The shell b' is provided at its top with an 10 upwardly-extending rim or flange, b^{11} , inclosing a seat, b^{10} , within which is received the water-section C, which in the bottom plate, 1, thereof has front receiving opening c^2 , corresponding with the discharge-opening b^{12} in the 15 broad covering-flange b^6 , which constitutes the top plate of the chamber B, and which in the top plate, 2, thereof has at the rear the discharging-opening c^3 . Between the front expansion-chamber c and the rear expansion-chamber 20 c' of this section are the intermediate connecting-tubes, c^4 c^4 c^5 c^5 c^6 c^6 , all of which are in transverse vertical section, preferably of the diamond or lozenge shape represented in Figs. 1 and 6, and the exterior or side tubes, c^6 c^6 , 25 which are vertical upon their exterior face, while upon the opposite side they are of a half-diamond form, as seen in the same figures. At or near their front and rear extremities the tubes c^5 are each provided with a short 30 vertical diaphragm or deflector, e' , which projects toward the side of the section in a plane perpendicular to the side of the tube. The tubes c^4 c^4 are provided with similar deflectors, e e , both of which extend from the sides of the 35 tube toward the center thereof, as seen in Figs. 3 and 6, while the tubes c^6 c^6 are without equalizing-deflectors or other means of restriction.

The water-section D has in the rear portion of its bottom plate, 3, a receiving-opening, d^2 , 40 corresponding with the discharging-opening c^3 of the water-section C, and in the front portion of its top plate, 4, it has discharging-opening d^3 , all as clearly represented in Figs. 2 and 4. The central tube, d^4 , of the section D, 45 like the tubes c^4 c^4 of the section C, is provided with coincident diaphragms f f , and the tubes d^5 d^5 at either side of the central tube, d^4 , have a single deflector, f' , while the tubes d^6 and d^7 , like the tubes c^6 in the section C, are from 50 end to end without obstruction. Of the remaining superposed parts the sections C' and C² correspond in construction with the section C and the section D' corresponds with the section D, as already described. The section 55 E, having wide depending flange E' and vertical passage E², has a top plate, 5, above the chamber or reservoir E³, such top plate being plain, while the bottom plate, 6, has longitudinal corrugations e' , which terminate at 60 the front in a reservoir or expansion-chamber, E⁶, which is produced by the enlargement or upward swell at this point of the top plate, 5, which is suitably tapped for the reception of the outflow-pipes F, any desired number of 65 which may be attached.

As will be readily understood, the intervals

between the several water-sections C, D, C', D', C², and E and the intervals between the several series of tubes c^4 , c^4 , &c., and d^4 , d^5 , &c., constitute the smoke spaces or flues of 70 the heater, the volatile products of combustion as they rise from the fuel-chamber taking a right and left zigzag course from bottom to top of the smoke-space by reason of the zig-zag or staggered arrangement of the series of 75 water-tubes. Passing through these smoke spaces or flues, which in the drawings are designated by the letter G, the products reach and are discharged into the exit-pipe H, which is fitted both to the top plate, 5, and the bottom plate, 6, of the top section, E.

By reason of their peculiar form, their sides flaring from the bottom outwardly and upwardly and from the top outwardly and downwardly, the water-tubes receive to the best 85 advantage the impact of the ascending heat-currents and thus thoroughly utilize the same, while ashes and other substances are prevented from accumulating upon their top surfaces.

The door I upon the flange or casing I', 90 which is composed of coincident projections upon each of the several horizontal water-heating sections C, D, C', D', C², and E, permits access to the smoke spaces or flues for repairing or cleaning the same, and for the insertion 95 between the water-sections and the adjustment in suitable position thereon of any desired number of baffle-plates K. When arranged as seen in Fig. 2, these plates cause a zigzag movement forward and backward of 100 the ascending products of combustion, a movement, it will be observed, quite distinct from and directly transverse to the right and left zigzag movement produced by the staggered arrangement of the water-tubes themselves. 105

It will be observed that, in the operation of the heater, as water is discharged from the inflow-pipes p it is received in the annular chamber b^9 at the base of the section B. From the chamber b^9 it quickly rises through the 110 tubular spaces s, formed by the corrugations b' upon the interior shell, b' , in conjunction with the plain surface of the exterior shell, b . At their points of nearest approach, as best seen in Figs. 5 and 8, the two shells are but 115 one-fourth of an inch apart, and it will be readily perceived that under the tendency of the moving currents of water to pass where friction is least these spaces s have practically the function and effect of flattened or oval tubes. 120 The space being preferably but about one inch in its greatest diameter, in transverse section, water within it is heated with great rapidity, and is quickly expanded in volume. This expansion finds its natural outlet in the 125 outwardly-projecting overhanging expansion-chamber b^{13} around the upper portion of the section, from which the water in a still more highly-heated condition is discharged into the broad transverse receiving-chamber c of 130 the water-section C. From this chamber, as already partially indicated, and as clearly

represented by the feathered arrows in Fig. 2, the volume of water, always in a spread-out or comparatively thin body, to render most quickly available the heat contained in the 5 escaping products of combustion, passes in a continuously but gradually ascending current from front to rear and from rear to front, until it is discharged into the top section, E, the bottom plate, 6, of which, by reason of 10 its corrugations, which extend at a right angle to the direction of the smoke-currents, becomes highly heated, thus still further expanding the volume of water at the moment of its exit from the heater into the circulating- 15 pipes, and thereby forcing its rapid circulation through them.

The natural tendency of the products of combustion to pass by the most direct course from the center of the fuel-chamber to the center of the exit-pipe opening, and thus produce 20 greatest rarefaction of the contents of the central members of the several series of water-tubes, and, as a consequence, an unduly-rapid circulation through the same, is counteracted 25 and the water-circulation is equalized through the provision of the vertically-arranged dia- phragms or deflectors $e' e'$ and $f' f'$, the effect of which is to check and retard the movement of the currents just in proportion to the remote- 30 ness of such tubes from the side walls of the heater. By this means complete equalization of the water-circulation is secured.

The return-flue openings p' will be provided at a point or points at a considerable distance 35 from the water-supply openings, as is customary.

It will be understood that wherever shown in the drawings the feathered arrows indicate the course of the water-currents and the un- 40 feathered arrows the direction of the smoke-currents.

It will be obvious, without explanation, that the number of sections C D employed in the heater might be either greater or less than the 45 number herein described and shown without changing the operation or affecting the character of the invention. It will also be evident that by skillful manipulation the section B might be cast in a single piece. It is much 50 more convenient, however, to cast the shells separately and attach them together; and this also has the effect of diminishing danger of fracture as a consequence of unequal expansion and contraction. It will be equally ap- 55 parent that the position of the receiving-opening of the lower horizontal water-section might be at the rear or at the side, instead of at the front thereof, without in any way affecting the principle of the invention; but at whatever 60 point such receiving-opening be provided the water-induction opening in the base-section should be on that side of the heater which is opposite the receiving-opening.

Having described my invention, I claim—

65 1. The water-chamber B, consisting, essen- tially, of a one-part annular or cylindrical in-

ner shell having vertical corrugations and an independent outer uncorrugated shell having water supply and return openings and top discharging-opening, the two distinct shells 70 in their main vertical portion being placed nearly in contact, so as to produce between them tubular intercommunicating water-pas- 75 sages, in combination with the superposed sec- tion C, having bottom receiving-opening, sub- stantially as set forth.

2. The two-part water-heating section B, embracing the shells b and b' and having in- 80 tervening annular chamber, b^9 , corrugations b' , forming passages s , as described, and inter- vening overhanging chamber, b^{13} , substantially as and for the purposes specified.

3. The combination, with the base or ash- 85 pit section A, having inwardly-projecting flange a^4 , of the exterior shell, b , having flange b^2 , and the interior shell, b' , having flange b^8 , the three flanges being seated one upon another, as shown and described.

4. The water-heating section B, having sub- 90 stantially cylindrical lower main portion and substantially quadrangular upper projecting portion, the upper portion constituting an expansion-chamber for the heated water-currents as they pass from the lower portion, substan- 95 tially as described and shown.

5. The water-heating section B, having the one-part inner shell, b' , extending as to its inner surface in a direct line from bottom to top, and having also the inclosing-chambers b^9 and b^{13} , the former encircling the lower ex- 100 tremity and the latter inclosing the upper ex- tremity of such inner shell.

6. In a hot-water heater, the combination, 105 with a lower water-heating and fuel-chamber section thereof, of a water-heating section rest- ing upon such lower section and having the front receiving-chamber, c , the rear discharg- ing chamber, c' , and the interconnecting wa- ter-tubes $c^4 c'$, which in transverse section are of diamond or lozenge form, substantially as 110 described.

7. The water-heating section B, having bot- 115 tom and top chambers, b^9 and b^{13} , for circula- tion in a horizontal plane, and the intermediate annular chamber for the upward move- ment of the water-currents, and having also inlet-opening at bottom and outlet-opening b^{12} at top, the two openings being at opposite sides of the section, substantially as specified.

8. The combination, in a hot-water heater, 120 of a lower water-heating section, which encircles the fuel-chamber of such heater and which discharges at the front top portion of such section, a horizontal section which has front and rear water-chambers, which extend across 125 the same from side to side, which has water- tubes which connect such front and rear trans- versely-extending chambers, and which is pro- vided in the rear portion of its top plate with a discharge-opening, and a horizontal water- 130 section, which is placed upon such lower hori- zontal section, which receives water through

an opening in the rear portion of its bottom plate, and which discharges water through an opening in the front portion of its top plate.

9. The combination, with the water-heating section B, constructed as described, of the superposed sections C, D, C', D', and C'', the upper plate of each of such superposed sections inclining upwardly from the receiving to the discharging end of the section.

10. The combination, with the water-heating and fuel-chamber section B, of the superposed sections C, D, C', D', and C'', each having upwardly-inclined top plate, and the top section, E, having bottom combustion-chamber embraced within the depending side flanges, the corrugated bottom plate, and top water-passage above such bottom combustion-chamber, substantially as set forth.

11. The combination, with the lower two-part water-heating and fuel-chamber section, B, having continuous corrugated inner shell and plain outer shell, of the upper water-heating section, E, having corrugated bottom plate, 6, plain top plate, 5, and the reservoir expansion-chamber E⁶, and the intermediate water-heating sections each having end water-chambers and a series of horizontal connecting water-tubes.

12. The combination, in the combustion-chamber section of a hot-water heater, of the water-heating sections C D, C' D', and C'', having transverse water-tubes and intermediate vertical flue-spaces, the water-tubes of each section being opposite the flue-spaces of the contiguous section, and the baffle plates K, resting transversely upon the water-tubes and arranged alternately at front and at rear of the combustion-chamber, the water-tubes serving to produce in the smoke-currents a zigzag movement from right to left and from left to right, and the baffle-plates operating to produce a zigzag movement of the ascending smoke-currents from rear to front and from front to rear, as specified.

13. The combination, with the water-heating sections D' C'', of the top section, E, having bottom expansion-chamber, E⁵, for the products of combustion, vertical water-passage E² at the rear, transverse water-expansion chamber E⁶ at the front, and top water-passage having corrugated bottom plate and connecting the passage E² with the upwardly-projecting reservoir or expansion-chamber E⁶.

14. The combination, with the lower sections, of the top section, E, having depending flanges, bottom combustion-chamber provided with top corrugations, and a smoke-exit pipe

which rises from the top of such combustion-chamber, the water-inlet passage extending from the bottom to the top of the section at 6 one end thereof, the water-outlet opening at the opposite end of the section, and the intermediate water-passage having bottom corrugations, substantially as described.

15. In a hot-water heater, an ash-pit section, 65 and a water-heating and combustion-chamber section which is annular in its main portion, which is rectangular in its upper portion, and which is provided with a water-discharging opening in its top plate, in combination with a 70 series of superposed hot-water sections, each lower section discharging through an opening formed in the bottom of the section immediately above it, and the water received at the base of the combustion-chamber section passing successively through each of the superposed sections in a continually-ascending current from 75 end to end thereof to its point of discharge at the top of the heater, substantially as set forth.

16. A hot-water heater which comprises an 80 annular water-heating and fuel-chamber-base section, and a series of superposed water-heating and combustion-chamber sections, each of which has a series of transverse water-tubes, the top plate of each of which is inclined upwardly from the inlet to the outlet end thereof, and each of which sections has a water-inlet opening in its bottom plate and a water-outlet opening in its top plate, and in which the currents of hot water pass by a zigzag course 85 from bottom to top, and in which the products of combustion pass in a zigzag course from bottom to top, the two zigzag currents moving, as to their horizontal course, at right angles to or transversely of each other. 95

17. In a hot-water heater, a series of horizontal water-tubes which have each an inclined top plate and which extend across the combustion-chamber of such heater, and which are provided with lateral equalizing-deflectors, substantially as and for the purposes specified. 100

18. The described intermediate water-heating sections, each consisting of the end receiving and discharging chambers having, respectively, a bottom and a top opening, and the interconnecting top inclined water-tubes, each diminishing in transverse dimensions from a point at or above its mid-height downwardly to the bottom. 105
